UNITED STATES PATENT OFFICE.

CLARENCE R. STEWART, OF SPOKANE, WASHINGTON.

GAME APPARATUS.

1,348,597.

Specification of Letters Patent. Patented Aug. 3, 1920.

Application filed September 27, 1919. Serial No. 326,719.

To all whom it may concern:

Be it known that I, CLARENCE R. STEWART, a citizen of the United States, residing at Spokane, in the county of Spokane and 5 State of Washington, have invented certain new and useful Improvements in Game Apparatus, of which the following is a specification.

This invention relates to improvements 10 in game apparatus and more particularly to toy catapults.

An important object of this invention is to provide a toy of the class described having novel means for throwing a small 15 projectile or missile in the direction of a target, said toy being provided with novel means for supporting the missile whereby the missile may be readily thrown out from the toy.

20 A further object of this invention is to provide a toy catapult having novel means for abruptly stopping the projectile throwing arm upon reaching the limit of its effective movement.

25 A further object of this invention is to provide a toy of the class described which is simple, of highly simplified construction and neat in appearance.

A further object of this invention is to 30 provide a toy catapult which may be safely used by both old and young as a source of pleasure.

A further object is to provide a toy catapult wherein the projectile throwing member 35 is adapted to be entirely controlled by the hand whereby the use of all triggers and catches may be dispensed with.

Other objects and advantages of the invention will be apparent during the course 40 of the following description.

In the accompanying drawing forming a part of this application and in which like numerals are employed to designate like parts throughout the same:

45 Figure 1 is a perspective of the device;

Fig. 2 is a central longitudinal sectional view through a slightly modified form of the invention;

Fig. 3 is a perspective of a modified form 50 of projectile throwing arm embodied in the invention.

Fig. 4 is a fragmentary vertical section through a modified form of target.

Fig. 5 is a perspective of a target embodied in the invention.

In the drawing wherein for the purpose

of illustration is shown several preferred embodiments of the invention, the numeral 5 generally designates a base which may be made of a light wood or other suitable material. An elongated handle 6 extends rearwardly from the base 5 and is of a lesser width than the base to enable the handle to be readily gripped.

In the form of the invention illustrated 65 in Fig. 1 the projectile throwing member generally designated by the numeral 7 is formed from a single length of wire bent in triangular formation to form converging arms 8, a bearing portion 9 and a bight 70 portion 10. The bearing portion 9 of the projectile throwing member is passed through staples 11 secured to the base and pivotally supporting the projectile supporting member. A coil spring 12 surrounds the bearing portion 9 of the projectile throwing member and has one terminal portion 13 engaging the base and its other terminal portion 14 engaging the rear side of one of the converging arms 8 for urging 75 the projectile member 7 forwardly or to an elevated position. The terminal portion 14 of the coil spring has its arm engaging portion curved as indicated at 15 for preventing accidental disengagement of the 80 terminal portion 14 with the projectile throwing member.

In the form of the invention illustrated in Fig. 1, a projectile supporting member 16 preferably formed of sheet metal is arranged on the outer portion of the projectile throwing arm 7 adjacent the bight 10 of the same and is provided with attaching flanges 17 which are curved about the arms 8 in gripping engagement with the same. 95 The central portion of the projectile supporting member 16 is provided with a concave recess 18 adapted for the reception of a projectile or missile 19 which in this case is in the form of a small ball.

One form of stop element or buffer 20 is illustrated in Fig. 1 and includes an upright metallic abutment 21 having its end portions 22 bent laterally and secured to the base by attaching flanges 23. If desired 105 forwardly extending attaching flanges 24 may be made a part of the abutment 20. To further brace the stop element or buffer, a pair of upwardly inclined rods 25 are anchored to the rear portion of the base as 110 indicated at 26 and are attached to the upper portion of the abutment 21 as indicated

at 27. The bracing rods may be of round wire or flat strips of metal and are connected to the abutment 21 immediately on the outer sides of the arms 8 and therefore serve to rigidly support the abutment and prevent the same from loosening.

In the form of the invention illustrated in Fig. 2 the abutment 21 and associated elements have been dispensed with and a pair of upwardly inclined stop arms 28 employed in lieu thereof. The forward ends of the stop arms 28 are provided with inwardly extending heads 29 which engage the projectile throwing member at a point spaced upwardly from the lower end of the same. The rear end portions 30 of the stop arms 28 are anchored to the base and serve to retain the arms 28 inclined upwardly as illustrated.

A further modification of the invention consists in providing a check cord 31 which is anchored to the base by an attaching eye 32 arranged adjacent to the bight portion 10 of the projectile throwing arm. The cord 31 may, if desired, be secured to the bight portion 10 of the projectile throwing arm or to a rearwardly disposed rounded extension 33 formed integral with the projectile supporting member 16. When the cord 31 is attached to the rearwardly disposed extension 33 the same is passed through an attaching opening 34 in the extension.

A modified form of projectile throwing arm is illustrated in Fig. 3 and is generally designated by the numeral 35. As in the form of the projectile throwing arm illustrated in Fig. 1 a single length of wire is bent in triangular formation to provide converging arms 36 and a bearing portion 37. The arms 36 are bent outwardly in semi-circular formation at points spaced from their rear ends as indicated at 38 to provide a projectile seat. The bight portion 39 of the projectile throwing member illustrated in Fig. 3 may, if desired, be connected to a check cord for limiting the forward movement of the projectile throwing member.

A target generally designated by the numeral 40 is adapted to be arranged forwardly of the catapult and includes an upright front 41, a base 42 and an inclined brace 43. A plurality of openings 44 are arranged in superposed spaced relation in the front wall 41 and are adapted to receive suitable projectile receiving pockets 45. Supporting devices 46 of a suitable nature are secured to the upper walls of the openings 44 and engage the pockets 45 for securing the same within the openings 44. As illustrated the pockets 45 are of various sizes and may be of any color, shape or design. The pockets 45 may also be arranged on the face of the target and about the openings 44. As illustrated in Fig. 4, the pockets 45 may be displaced by a plu-

rality of disks 47 arranged within the openings 44 and pivotally suspended from hangers 48 secured to the top walls of the openings. The disks 47 which may be of any shape or design are adapted to be swung upon the pivots 48 upon being engaged by the missile from the catapult.

In the practice of the invention the catapult is arranged a selected distance forwardly of the target and the projectile throwing arm is drawn rearwardly in contact with the base and against the tension of the coil spring. A missile or projectile is now arranged within the seat and upon releasing the projectile throwing member the missile is shot in the direction of the target. In the form of the invention illustrated in Fig. 1, the projectile throwing member is abruptly stopped in its forward movement by the abutment 21. In the form of the invention illustrated in Fig. 2, the projectile throwing member is abruptly stopped in its forward movement either by the stop arms 28 or the flexible elements 31.

When it is desired to reset the catapult, it is merely necessary to manually draw the projectile throwing member rearwardly to a horizontal position and place the projectile or missile within its seat. Upon releasing the projectile throwing member the missile is thrown forward with considerable velocity and as the projectile throwing member is abruptly stopped in its forward movement further impetus is given the missile.

With reference to the foregoing, it will be noted that I have provided an extremely simple toy catapult which is of durable construction and which may be used without the possibility of injuring the hands as a result of the action of the spring of the projectile throwing member. As is obvious from Fig. 1 the projectile throwing member is controlled entirely by hand without the aid of triggers, catches, etc., as is usual in devices of this character.

It is to be understood that the forms of the invention herewith shown and described are to be taken as a preferred embodiment of the same and that such minor changes may be made as will remain within the spirit of the invention and the scope of what is claimed.

Having thus described the invention, what is claimed as new is:

1. A toy catapult including a base, a projectile throwing member having a transverse bearing arm and a pair of arms, means to rotatably connect said transverse arm to said base, a spring for tensioning the said projectile throwing member, and a projectile supporting plate having its end portions formed with flanges secured about the rear end portions of said arms, said projectile supporting plate being provided with a centrally arranged projectile receiving recess.

2. A toy catapult including a base, a projectile throwing member having a transverse bearing arm and a pair of arms, means to rotatably connect said transverse arm to said 5 base, a coil spring surrounding said transverse arm and tensioning the said projectile throwing member, a projectile supporting plate having its end portions formed with flanges secured about the rear end portions 10 of said arms, said projectile supporting plate being provided with a centrally arranged projectile receiving recess, and a buffer secured to said base and adapted to be engaged by said converging arms.
- 15 3. A toy catapult including a flat base having a rearwardly extending elongated handle, a projectile supporting member mounted on said base and provided with converging arms and a transversely extending bearing arm, means to rotatably connect said bearing arm to said flat base, a spring having engagement with one of said converging arms for urging each of the converging arms forwardly, a projectile supporting plate mounted on the rear end portions 20 of said converging arms, and a buffer formed from a flat plate having its end portions extended rearwardly and downwardly and secured to said base, and forwardly extending 25 bracing arms secured to base and to said buffer outwardly of said converging arms.
- 25 4. A toy catapult including a flat base having a rearwardly extending elongated handle, a triangular projectile supporting member mounted on said base and provided with converging arms and a transversely extending bearing arm, means to rotatably connect 30 said bearing arm to said flat base, a coil spring surrounding said bearing arm and having engagement with one of said converging arms for urging each of the converging arms forwardly, a projectile supporting plate mounted on the rear end portions of said converging arms, and a buffer formed from a flat plate having its end portions extended rearwardly and downwardly and secured to said base, and forwardly extending 35 bracing arms secured to base and to said buffer outwardly of said converging arms.
- 35 5. A toy catapult comprising a base, a projectile supporting member pivotally mounted upon said base, spring means for urging said projectile supporting member forwardly, a buffer formed from a flat plate having its end portions extended rearwardly and downwardly and secured to said base, and bracing arms secured to the intermediate portion 40 of said base and secured to said buffer outwardly of said projectile supporting member.
- 40 In testimony whereof I affix my signature.
CLARENCE R. STEWART. [L.S.]
